[57] CLAIM

The ornamental design for a cruciform key medal, as
shown.

DESCRIPTION

FIG. 1 is a perspective view of a cruciform key medal
showing my new design;

FIG. 2 is a front elevational view;

FIG. 3 is a rear elevational view;

FIG. 4 is a top plan view; and

FIG. 5 is a sectional view taken along the lines 5—5 of
FIG. 2.
